UNITED STATES PATENT OFFICE.

JOHN HENRY CHATAIGNE, OF RICHMOND, VIRGINIA.

BLOTTING-PAD.

SPECIFICATION forming part of Letters Patent No. 246,461, dated August 30, 1881.

Application filed June 22, 1881. (Model.)

To all whom it may concern:

Be it known that I, JOHN HENRY CHATAIGNE, of Richmond, in the county of Henrico and State of Virginia, have invented certain new and useful Improvements in Blotting-Pads; and I do hereby declare the following to be a full, clear, and exact description of the invention, such as will enable others skilled in the art to which it pertains to make and use it, reference being had to the accompanying drawings, which form a part of this specification.

My invention relates to a combined blotting-pad, paper-cutter, rule, ruler, calendar, and memorandum-tablet; and it consists in taking a sheet of thin metal, stamping or otherwise cutting a large opening through its center, and then turning over the two edges, so as to form grooves or guides, in which the blotting-paper, calendar, and memorandum-tablet are placed, as will be more fully described hereinafter.

The object of my invention is to combine with a blotting-pad the several articles above enumerated, so as to have them all in a simple, convenient, and compact form, so that any one of them may be used at any time.

Figure 1 is a plan view of my invention. Fig. 2 is a longitudinal vertical section of the same. Fig. 3 is a vertical cross-section. Fig. 4 is a perspective of the metal frame by itself.

A represents the frame, which is made from a piece of sheet metal of any desired width and length, and through the center of which is made a large opening, B. This opening is made just large enough to leave but a narrow strip of metal along each side and at one end, so as to allow as large a portion as possible of the blotting-pad to come in contact with the paper. The edges of the sides of the frame are turned over upon the top, so as to form the grooves or guides C, in which the blotting-pad D, the calendar E, and a memorandum-tablet, F, are placed. At one end of one or both of these guides is formed a suitable stop, G, which prevents the paper from slipping too easily out of position, while the other end of the two guides is left entirely clear, so that the papers can be slipped readily into place. Formed upon the edges of these two turned-over parts are the curved projections H, which serve as handles, by means of which the implement can be readily handled.

Upon the top of the blotting-pad is placed a card, upon which is printed a calendar, and to which may be attached a memorandum-tablet. The calendar, being upon the top, may be readily consulted at any moment without in any manner interfering with the use of the blotting-pads.

By placing the blotting-pads in guides, as here shown, they will never become torn or have their ends turned up, so as to make them unsightly and unfit for use.

Upon the top of one of the edges is marked a rule, I, which may be divided off into spaces of any length, and the outer edge of this rule forms a ruler.

Upon the opposite side a small strip, L, of the sheet metal is turned backward upon itself, and this turned-back strip, cut to a true straight edge, forms a paper-cutter.

Upon the top of either side of the frame, or preferably upon the side upon which the paper-cutter is formed, there is secured a pencil-holder, Q, in which a pencil is kept for the purpose of writing upon the tablet.

One end of the frame is extended, as shown at R, so as to have a hole made through it, by which the frame may be hung up when not needed for immediate use, and may also be used for printing or painting advertisements thereon.

This invention will be found a useful article for the counting-room, office, store, or place of business of any kind where pen, ink, and paper have to be used.

The blotting-pad, the tablet, and calendar, being loosely held in position, can be instantly removed and replaced at any time.

Having thus described my invention, I claim—

A frame for holding blotting-pads, having the hole B made through its center, so that the pad can come in contact with the paper written upon, having its edges turned over upon its top to form guides to hold the paper, and having a portion of the cut-away metal turned back, so as to form the paper-cutter L, substantially as set forth.

In testimony whereof I affix my signature in presence of two witnesses.

JOHN HENRY CHATAIGNE.
